UNITED STATES PATENT OFFICE

2,214,770

FREQUENCY AND AMPLITUDE SOUND CHANGER

Howard McCurdy, Walnut Park, Calif.

Application June 7, 1938, Serial No. 212,279

5 Claims. (Cl. 181—35)

This invention is a frequency and amplitude sound wave changer and is an improvement in the type of apparatus set forth in my U. S. Patent No. 2,113,055.

5 In that apparatus the incoming, cylindrical stream of gas, as the exhaust from a combustion motor, is divided into gradually decreasing, coaxial beams and these were each expanded, in its own relative portion of an elongate cylindrical 10 chamber formed in advance of a transverse center-perforate barrier, each arrested part of the stream perpendicularly impacting its barrier before its flow was arrested. The abruptly stopped part of the stream was allowed to expand in an 15 elongate space between two opposite end barriers and then to pass radially to atmospheric air pressure through lateral ports in the apparatus. While this greatly reduced the amplitude of exhaust waves these could be sensed in some surrounding area in certain range around the 20 muffler.

The present invention involves the same principle of expansion chambers and barriers but aims to so break up and expand the stream of 25 gas as to obtain a higher degree of efficiency in destroying the amplitude of the sound waves.

An object is to provide means for intercepting the fractions (cylindric, concentric layers) of the wave forming stream just as the layer initially 30 enters its relative breaker or expanding chamber; this being otherwise unobstructed in any manner transversely or longitudinally so that each shaved-off layer can expand as a tube in an expansion space of much length existing between 35 the shaving-off means and the next following reduction barrier. In other words the advancing, cylindric layer of gas is first shaved off and obliquely deflected and then progressively flows, as will be shown, to and along its expansion 40 chamber, instead, as in the said patent device, of being sliced off and directed straight radially and then substantially reversed in flow (toward the entrance) before its escape to the atmospheric ports.

45 Further, an object is to provide for the division of each concentric layer of the gas stream into sub-divisions or layers, as may be desirable in destroying high amplitude waves of sound incident to some stimuli.

50 Also, it is an object of the invention to provide for the elimination of reversing moments in the gas stream flow and the undesired diffraction of the sound waves, to eliminate outlets radially of the axis of the stream, and to effect a generally 55 or principally unidirectional flow the sliced-off,

expanding and expanded concentric, annular fractions of the parent stream of gas.

Additionally, an object of the invention is to provide a sound controlling device in which a parent stream is divided into substantially, transverse, equal concentric layers and for the expansion thereof in substantially equal volume chambers to avoid undesired differential reaction as between the several layers.

Carrying the invention further, an object is to 10 provide a muffler affording a series of coaxial, axially elongate, concentric, progressively decreasing cross-area expansion chambers which are commonly open, that is without radial obstruction, for the effective length of their gas 15 expanding portions, to the axis of a path of gas flow and which chambers are each longitudinally unobstructed except for a relatively shallow, transverse, conoidal annulus concentric to the axis, and the chambers in echelon relation on the 20 axis and all preferably opening to atmosphere in one (axial) direction.

And further, an object is to provide means for negating as far as desired diffraction of the sound 25 waves in reverse as to the line or path of axial discharge from the device as by the provision of suitable transverse louvers of circular form.

The invention consists of certain advancements in this art as set forth in the ensuing disclosure and having, with the above, additional objects and 30 advantages, as hereinafter developed, and whose construction, combinations and details of means, and the manner of operation will be made manifest in the description of the herewith illustrative embodiment; it being understood that modifications, variations and adaptations may be 35 resorted to within the scope, spirit and principles of the invention as it is more directly claimed hereinbelow.

Figure 1 is an axial section of the silencer. 40

Figure 2 is a transverse section on line 2—2 of Fig. 1.

Figures 3 and 4 are detail views of a sinuous edged baffle.

In this adaptation of the wave changer to an 45 internal combustion motor, the exhaust gases therefrom are received in a conduit 2 which is fixed concentrically in a rearwardly flared first end wall 3' of a first stage chamber or cylinder 3 of a diameter of greater dimension than that of 50 the conduit 2 at its connection with the end wall 3' which is provided with a central intake opening 3'' of substantially the size of the bore of the exhaust pipe or conduit 2.

The chamber 3 in this disclosure extends rear- 55

wardly of and is in concentric spaced relation to the contiguous intruded end of a second expansion chamber 5 having a front end wall 4 provided with a concentric round opening 4' which 5 is of suitably less diameter than the first intake opening 3'' in wall 3' of chamber 3. This stage wall 4 is preferably in the form of a conoidal annulus and its obliquity is rearward or with the axial gas path of flow, and presents an appreciable 10 frontal area 4^a across the projected bore at the intake opening 3''; this is clearly depicted in Fig. 1. It will be noticed that there is no obstacle between the axis of the chamber 3 and its inner surface for the length of that part of the 15 chamber between walls 3' and 4 excepting for means positioned near the front wall 3' and which has the function of checking back and slicing off the outermost annular layer of the exhaust stream incoming at the opening 3'. This first-stage slicing 20 means may include one or more, here two, slightly axially spaced, rearwardly pitched, conoidal annuli 3^b and 3^c the forwardmost of which has a flow hole somewhat smaller than the intake opening 3' and the latter of which, 3^c, 25 has a flow hole of the same size as that, 4', leading to the second stage expansion chamber 5.

Thus the first cutting ring 3^b takes or slices off a concentric outermost layer of the incoming stream and deflects it obliquely outwardly and 30 rearwardly. This feature of the invention permits the sliced off layer of gas under pressure to freely expand in that space between wall 4 and the ring 3^c and radially between the stream of gas flowing through the second ring 3^c (and moving 35 as a core toward the equi-size hole 4' in the wall 4) and the chamber wall 5.

This is a wholly different expanding function than was possible in the form of device of said patent where the gas had first to be stopped by 40 the equivalent wall 4 to be sliced off, whence it was expanded by a reversal of flow toward the front end. In the present invention the gas is sliced off and expands as it flows unidirectionally with the main stream toward the far, 45 discharge end of the silencer.

The far end of the second stage chamber 5 is in spaced, concentric relation with a suitably smaller, third expansion chamber 7 having a rearwardly pitched, conoidal, front end wall 6 50 with a central opening 6' materially smaller than the opening 4' of the second stage so as to present a substantial abutment area 6^a or closure for its end of the chamber 5 to permit a reduced core 55 of the stream of gas to flow into chamber 7 for expansion. However, as in the case of chamber 3, the chamber 5 has near the forward wall 4 a slicing off means in the form of a plurality of slightly axially spaced, conoidal rings 5^b and 5^c the first, 5^b, of which is provided with a central 60 hole somewhat smaller than the hole 4' but larger than the hole of its associate ring 5^b which, in turn, is about equal to the hole 6' in wall 6. The core of the stream passing the hole in the secondary slicing ring 5^c flows on to and enters 65 the chamber 7 by way of the wall hole 6' but that layer of the stream which is intercepted by the slicing rings 5^b and 5^c is directed obliquely rearwardly toward the cylinder wall 6 to be freely expanded in the space therein concentrically 70 about the fast flowing central core of the gas stream moving toward the wall 6. The effective expansion chamber space in section 5 is unobstructed in any way except for the slicing off means 5^b—5^c.

75 The core stream passing through the wall

opening 6' is sliced just back of the wall 6 by a rearwardly pitched, conoidal ring 7^b to be directed obliquely rearwardly for expansion in the space concentrically surrounding the final small stream core of gas permitted to flow past the 5 opening in the ring 7^b.

The far end of the chamber 7 is concentrically spaced about a closed filler or body 9.

From the above it will be seen that the expanded gas flows from chamber 3 by way of an 10 annular outlet port 3x; that from chamber 5 flows from an annular exhaust port 5x, and that from chamber 7 from an annular exhaust port 7x; with all of the spent gases moving in a common, unidirectional, axial stream. It is understood 15 that while this is the preferred exhaust principle, lateral outlets may be employed if so desired in any or all of the chambers in combination or not with the axial direction exhaust ports. 20

The width or radial dimension of the several slicing off rings, from their bore hole to their rims is preferably of such a degree as to best effect the slicing operation and permit, then, the least barrier to the flow of the layer of the stream 25 over the rim of the ring into the rearward, relative expansion space.

There is shown in Figs. 3 and 4, a modification of the form of slicing element as comprising a 30 conoidal annulus 10 having a plurality of symmetrical, angularly spaced fins or blades 11 with radial edges 12 and arcuate edges 13 from the tips of the fins to the roots of the radial edges in order around the annulus so as to provide flow openings, within the circle enclosing the tips of the fins, to effect the flow of the interrupted layer of gas in streams of differential rate of speed, or relative starting time, toward the expansion chamber in rear of the relative annulus 10 to best utilize the expanding capacity of the 40 chamber by smoothing out the stream instead of tending to choke the stream by diverting the full layer into the chamber at one instant. If and when preferred, the fins 11 may be given a common helical pitch as here indicated to helical- 45 ly swirl the expanding gases.

A narrow, annular, inwardly projecting, rearwardly inclined sound arresting ring 15 may be fixed in the outlet end of each of the expansion chambers, as indicated in Fig. 3. 50

Because of the reduced diameters of the several expansion chambers 3—5—7, the exhaust end of each may be provided with a suitable number and size of circular louvers 16. Or the difference in area can be equalized by proportioning the 55 chamber diameters to give the desired size of vents. While the louvers 16 are shown as of conoidal form, it is understood that their shape and angle may be varied to suit. Also the length of the chambers may be varied to give equal or 60 unequal volumes of expansion for fluids and to vary or equalize the time lags between the subdivisions of the exhaust stream.

The sinuous edges of the exhaust baffle 10 constitute a means to cause the sound wave to be 65 gradually diffused. In Fig. 1 the end of one chamber of the apparatus is shown as having an end edge in the form of one full pitch of a helix H, with the result that the exhaust stream and sound wave passing over this sinuous edge is gradually retarded in its discharge to the atmosphere in a circle around the terminal. 70

What is claimed is:

1. A sound wave changer having an annular, 75 exhaust conduit member having an opening

whose edge is a concentric helix and the axial width of the opening being substantially a full pitch of the helix around the axis of the member; said helical discharge edge operating to effect the gradual, processional diffusion of a wave body in a helical, radial form to lesser outer pressure space and said edge preventing higher amplitude portion of the wave from passing at one instant in any material angular degree in one transverse plane.

2. A sound wave changer having an annular, open end exhaust member whose discharge end edge is a helix over which a stimulated fluid wave is processionaly dissipated while passing out of the open end of the member.

3. A sound wave changer including a discharge member having a flow opening to its bore and

the edge of which includes a helix and the opening having an axial length about equal to one pitch of the helix and operative to prevent diffusion to any material amount in any transverse plane of the opening.

4. A sound wave changer including an exhaust tube whose outlet end is in the form of a concentric helix along its edge; whereby to cause dissipation of discharging fluid only as an infinite number of axially isolated pencils radial 10 to the helical edge of the outlet from the tube.

5. An exhaust tube whose wall terminates progressively along its length in the form of a helix of substantially one full pitch and the ends of the helix being joined by a substantially longitudinal edge part of the tube.

HOWARD McCURDY.
